[57] CLAIM

I claim the ornamental design for a simulated cross drilled disc brake cover, as shown and described.

DESCRIPTION

FIG. 1 is a perspective view of the simulated cross drilled disc brake cover;

FIG. 2 is a front elevational view of the simulated cross drilled brake cover;

FIG. 3 is a side view of the simulated cross drilled brake cover (the bottom and top view being identical to the side view);

FIG. 4 is a rear elevational view of the simulated cross drilled brake cover;

FIG. 5 is a perspective view of the simulated cross drilled disc brake cover showing a second embodiment with a polished surface;

FIG. 6 is a front elevational view of the simulated cross drilled brake cover showing a polished surface;

FIG. 7 is a side view of the simulated cross drilled brake cover (the bottom and top view being identical to the side view) showing a polished surface; and,

FIG. 8 is a rear elevational view of the simulated cross drilled brake cover showing a polished surface.
